Primary Examiner — Robert M Spear*Assistant Examiner* — Darcey E Heflin(74) *Attorney, Agent, or Firm* — Nixon Peabody LLP;
Jeffrey L. Costellia**CLAIM**

I claim, the ornamental design for a portable information terminal, as shown and described.

DESCRIPTION

FIG. 1 is a front view of a portable information terminal showing our new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof; and,

FIG. 7 is a front perspective view thereof.

The broken lines in the figures show portions of the portable information terminal which form no part of the claimed design.

The portable information terminal can function as a computer, a media reproducing device (e.g., a music player, a movie player, or a game player), a media storage device, a communication device (e.g., a portable telephone), or the like, for example. The portable information terminal is wearable on an arm, a leg, or the like.
